INVENTOR
Conrad Dressler

John E. Hubbard
ATTORNEY

UNITED STATES PATENT OFFICE.

CONRAD DRESSLER, OF CLEVELAND, OHIO, ASSIGNOR TO AMERICAN DRESSLER TUNNEL KILNS, INC., OF CLEVELAND, OHIO, A CORPORATION OF NEW YORK.

METHOD OF AND APPARATUS FOR ENAMELING.

Application filed July 13, 1921, Serial No. 484,318. Renewed February 18, 1925.

To all whom it may concern:

Be it known that I, CONRAD DRESSLER, a subject of the King of Great Britain, and a resident of Cleveland, in the county of 5 Cuyahoga and State of Ohio, have invented certain new and useful Improvements in Methods of and Apparatus for Enameling, of which the following is a specification.

My present invention consists in an improved method of and apparatus for enameling metal; and the general object of my invention is to provide for the effective utilization of a tunnel kiln in enameling sheet iron sign plates and analogous articles. 15 More specifically the object of my present invention is to provide for the efficient simultaneous enameling of both sides of plate like articles.

In enameling a sheet metal article such as 20 a sign plate which, unlike a pot, is not shaped to resist bending stresses, it is ordinarily necessary to enamel the article on both sides, to prevent the article from warping as a result of the temperature changes 25 in different portions of the article occurring when the enamel formed material melts. Such warping tendency is avoided when both sides of the article are enameled at the same time provided the enameling material and the heat are similarly applied to the two sides of the article. In the case of enamel signs and the like, it is generally desirable also to enamel both sides of the article to avoid oxidation.

30 My invention comprises special provisions for transporting articles to be enamelled through the enameling kiln and for simultaneously subjecting the two sides of each article to practically the same enamel manufacturing temperatures.

The various features of novelty which 35 characterize my invention are pointed out with particularity in the claims annexed to and forming a part of this specification.

40 For a better understanding of the invention, however, and its advantages, reference should be made to the accompanying drawings in which I have illustrated a preferred embodiment of my invention.

45 Of the drawings:

Fig. 1 is a transverse section through an 50 enameling kiln; and

Fig. 2 is a side elevation partly in section 55 on the line 2—2 of Fig. 1.

In the drawings, A represents a tunnel

50 kiln provided with track rails B at its bottom for a goods carrying car or truck C. The kiln is heated by combustion chambers D resting on benches A' at the sides of the passage way for the body of the car C. The combustion chambers D through which the burning gases and products of combustion pass lengthwise of the kiln have their heating walls formed with circulating channels D' through which a convection current circulation of the kiln atmosphere is set up as in the ordinary Dressler kiln. Preferably, however, the inner side walls of the combustion chambers are more greatly inclined from the vertical than is usual in an ordinary Dressler kiln and are formed with windows D² opening from the corresponding channels.

55 The truck C is formed with a superstructure having provisions for supporting the sign plates or like flat articles S at a suitable elevation. Preferably, as shown, the articles are horizontally disposed to prevent the enamel from running when it melts. In the particular construction shown, the truck superstructure comprises cast iron standards E in the form of webs extending transversely to the length of the kiln and longitudinally disposed bars F adjustably supported on the standards E and provided on their upper sides with suitably spaced pins or finger-like projections F' on which the articles S rest. Advantageously the metallic body or framework of the truck is covered by refractory material H shaped to provide oppositely inclined surfaces H' which intersect along the center line of the truck and tend to reflect heat from the side of the tunnel upward against the undersides of the articles S.

60 In the operation of the apparatus shown in the drawings, the upper sides of the articles S receive heat by radiation from the crown A² of the kiln and by contact from the convection currents of the kiln atmosphere. The undersides of the articles S also receive heat by contact from the kiln atmosphere though to a lesser extent than the upper sides of the articles. In addition the undersides of the articles S also receive radiant heat from the top surfaces H' of the refractory portion H of the car body and receive radiant heat through the windows D² from the adjacent inner walls of the channels D'. Advantageously, as shown, the articles S project beyond the sides of

the body of the truck C and overhang the combustion chambers D. By suitably proportioning the kiln car parts it is possible with the construction shown to supply heat 5 at about equal rates to the upper and lower sides of the articles so that the enamel forming material with which the two sides of the articles are coated melt at approximately the same time and rate and the tendency to 10 warp the plates is thus practically eliminated. Advantageously the kiln is so heated and the goods so moved into and through the kiln chamber that the articles are very quickly brought to the enamel melting temperature and are then maintained at that temperature until the enamel melts or sets.

The kiln and kiln car may, aside from the special features referred to above, be of the type disclosed in the patent to Meehan No. 20 1,348,510 though other types of kiln and truck construction may be employed.

While in accordance with the provisions of the statutes I have illustrated and described the best form of apparatus embodying my invention now known to me, it will be apparent to those skilled in the art that changes may be made in the form of apparatus disclosed without departing from the spirit of my invention as set forth in the 25 appended claims and that certain features of my invention may sometimes be used to advantage without a corresponding use of other features.

Having now described my invention, what 30 I claim as new and desire to secure by Letters Patent, is:

1. The method of enameling both sides of flat articles in a tunnel kiln of the muffle type by means of a convection current circulation of the kiln chamber and radiant heat, which consists in supplying heat at 40 substantially the same rate to each side of

the article by setting up a convection current circulation of the kiln atmosphere in directions transverse to the length of the kiln 45 while holding the articles in a horizontal position in the kiln chamber with their upper sides exposed to radiant heat from the roof of the kiln and their lower sides exposed to radiant heat from the hot kiln 50 walls at the sides of, and beneath, the articles.

2. A kiln car formed with a body portion and a skeleton superstructure carried thereby and comprising spaced apart standards 55 extending transversely to the direction of car movement, and work supports mounted on said standards and provided with upwardly projecting fingers on which the articles to be enameled may rest.

3. A kiln car comprising a skeletonized article supporting superstructure and a body portion covered with refractory material shaped to upwardly reflect heat coming from heat radiating surfaces at the sides of 65 the car.

4. A kiln comprising a kiln chamber, combustion chambers at the sides of the goods pathway through the chamber and formed with open ended channels in their walls extending transversely to the length of the kiln for setting up a convection current circulation of the kiln atmosphere and having their walls adjacent the goods pathway inclined away from the vertical and formed 70 with windows in the last mentioned wall opening from the said channels therein, and means for supporting the articles to be heated in the kiln so that their under sides receive radiant heat through said windows.

Signed at New York, in the county of New York and State of New York, this 11th day of July A. D. 1921.

CONRAD DRESSLER.
